ABSTRACT: A phototypesetting system employs a cathode-ray tube to present characters of typesetting quality wherein each of the characters displayed is generated by directing the cathode-ray tube beam to a series of locations, each immediately adjacent its previous location, where the beam is energized for a predetermined period of time. A character memory, such as an optically encoded disc, supplies digital information to electronic circuitry which initially locates the beam within a character field and then directs the beam sequentially to additional locations, each of the locations immediately adjacent the previous location, thus forming characters from a series of illuminated spots. Additional deflection signals are supplied to control the cathode-ray tube to move the beam automatically to the next character position after each character has been formed in preparation for the writing of subsequent characters.

RELATED APPLICATIONS

Reference is hereby made to U.S. Pat. application Ser. No. 591,734, filed Nov. 3, 1966, entitled **TYPESETTING SYSTEM**; Ser. No. 608,161, filed Jan. 9, 1967, entitled **ENCODER READ OUT APPARATUS**; and Ser. No. 805,105, filed concurrently herewith entitled **CHARACTER MEMORY**.

BACKGROUND OF THE INVENTION

High speed phototypesetting devices using cathode-ray tubes are commonly employed to display characters for subsequent recordation on photographic film. Different types of character generators have been used to form these characters, such generators including character grids used in conjunction with a scanning video tube, or core matrix or magnetic drum memories which are used to generate the characters by scanning the character field in a raster scan pattern either by forming the characters from a series of lines with the cathode-ray tube beam being energized only in those areas where the character is present, or by turning the beam off and on as it is moved in a series of incremental steps in the raster pattern.

One disadvantage of the raster scan type of character generating systems lies in the fact that valuable time is being wasted while the beam control circuitry attempt to direct the beam to areas which form no part of the character, and where the beam therefore remains deenergized.

This invention relates to an improved typesetting apparatus wherein the characters may be formed by moving a beam of energy, such as the electron beam of a cathode-ray tube, to a plurality of discrete locations in a predetermined sequence and energizing the beam of energy at each of those locations for a predetermined period of time. The beam is therefore never directed to an area which forms no part of the character, with the result that the character is generated in a minimum of time.

Each of the characters in a font of type is represented by digital information recorded in character memory means, such as an optical character memory adapted to be rotated at a relatively high rate of speed. The digital character information is recorded as a series of bytes, each consisting of three bits, each byte forming an instruction to cause the beam to move to one of the locations immediately adjacent its previous location. The character is therefore formed by focusing a beam of energy onto the energy responsive surface of the tube and moving the beam to a plurality of predetermined locations by modifying the output of a circuit which controls the vertical and horizontal location of cathode ray tube beam in discrete increments. Although a three-bit code is used to move the beam to a new location and expose the film, as opposed to the single digit code used to control the intensity of the beam in those character generators wherein the characters are formed by scanning a portion of the cathode-ray tube face in a raster pattern, it has been found that the time for character generation is nevertheless reduced since the beam is never directed to a location which does not form part of the character.

A group of codes are associated with each character track on the optical character memory to supply control information to the electronic circuitry used in the formation of the characters. For example, it has been found that more rapid access to the character information may be accomplished by dividing each character into a plurality of sections, and supplying each of those sections with a code identifying the starting coordinates of that section with respect to the remainder of the character. A more complete explanation of this type of character generation may be found in the above mentioned copending U.S. Pat. application, Ser. No. 805,105. Also, the number of sections required to form a complete character may be included as part of the control information, thus providing for flexibility in the generation of the character.

The control information may also include codes indicating the normalized width of the character, which, when multiplied with the actual horizontal point size of the character being displayed, will give a signal which will cause the beam of energy 5 to be moved to the proper horizontal location after the formation of that character is completed. Still another portion of the control data may indicate the point size of the recorded character which, when multiplied with the vertical an horizontal point size, will produce signals controlling the size of the character formed as well as the time during which the beam is energized in each location.

Accordingly, objects of this invention are to provide an improved method and apparatus for generating characters of typesetting quality by energizing a beam of energy to form a 10 spot and positioning the spot at a plurality of predetermined, immediately adjacent locations within a character field in information from a character memory, each of the locations forming the character being identified by reference to its immediately preceding location, without directing the beam into 15 areas which form no part of the character; to provide a method and apparatus for generating characters of typesetting quality wherein the characters are formed from a plurality of spots, the spacing between spots being consistent within a 20 character, and the spot size relative to the total size of the character being predetermined to produce characters of high resolution; to provide a method and apparatus for forming characters of typesetting quality wherein the digital information representing a character is stored on a cyclically moving 25 memory, and wherein rapid access to the character information 30 is provided by dividing each character into a number of sections with the location of each section within the character field being so identified that a complete character may be 35 formed from any sequence of sections which make up a complete character, and with the generation of each section being accomplished by moving the beam sequentially to a series of predetermined locations first with reference to the starting location of that section and afterwards with reference to the previous location of the beam; and to provide a 40 typesetting method and apparatus wherein characters may be displayed an area at a time, with the intercharacter spacing being automatically provided in response in a stepwise manner to the size of the character actually formed as indicated by the 45 point size of the character stored in the character memory and selected by a control record. **BRIEF DESCRIPTION OF THE DRAWINGS**

FIG. 1 is a diagrammatic view of a system for generating characters of typesetting quality on the face of a cathode-ray tube with a part of the system shown as electrical block diagrams;

FIG. 2 represents a character memory and illustrates the recorded information representing a character being repeated about the character memory with each repetition being divided into a number of sections;

FIG. 3 is an enlarged view of a portion of the character memory disc shown in FIG. 2, with two clock tracks and a single discrete character track being shown;

FIG. 4 is a diagram showing the direction in which the cathode-ray tube beam moves in accordance with the numerical instructions derived from the character memory;

FIG. 5 is an enlarged view of the letter *a* made up of several numbers, each number representing an instruction for moving the cathode-ray tube beam to a location immediately adjacent its present location to form the character;

FIG. 6 is an enlarged view of a portion of the letter *a* shown in FIG. 5 showing how the cathode-ray tube beam is moved in response to specific instructions from the character memory to form the character;

FIG. 7 is an electrical block diagram for a phototypesetting system incorporating the features of this invention;

FIG. 8 is an electrical block diagram of the character generator used to form characters such as that shown in FIG. 5;

FIGS. 9A through 9D are detailed logic diagrams of a portion 75 of a character generator including the registry entry

counter, the distribution gates, the skip counter and the section counter;

FIGS. 10A through 10D are detailed logic diagrams showing the control logic of the character generator of his invention;

FIGS. 11A and 11B are detailed logic diagrams of the clock used to control the character generator of this invention in response to clock signals from the character memory;

FIGS. 12A and 12B are detailed logic diagrams showing the x and y up-down counters, the PREDIPS register and the normalized width register.

DESCRIPTION OF THE PREFERRED EMBODIMENT

Referring now to FIG. 1 which shows in part a block diagram of a device for generating characters of typesetting quality on a cathode-ray tube, the character storage memory is shown schematically at 10 and is formed from a transparent disc having alphanumeric characters optically stored thereon as a plurality of digital bytes which may be presented in a sequential manner. The character storage memory may be similar in its construction and arrangement of tracks containing character information to that character storage memory shown and described in copending U.S. Pat. application Ser. No. 608,161, filed Jan. 9, 1967, and assigned to the same assignee as the present invention. In that copending application, an optically transparent character storage memory is described as containing six bands, with each of the bands containing 35 discrete tracks having optical marks permanently recorded thereon.

While a single discrete track is herein described as containing the information for a single character in serial form, it is understood that a plurality of tracks, usually adjacent, may also be used to represent in parallel form the information required for the generation of a single character. In either case, the information for character generation will be regarded as being contained in a single discrete track in this application. It is also understood that a plurality of character storage memories may be provided and that a pickup device is associated with each of the bands on each of the character memories. Either mechanical or electronic switching may be employed to select the character storage memory to be used and the particular band within the selected memory.

The digital information contained within the tracks on the character memory 10 is illuminated by a light source 11 and the image of a plurality of these tracks is projected onto a fiber optic pickup assembly 12 where that image is optically magnified and focused onto individual fiber optic bundles 13 and transmitted by means of these bundles 13 to photomultiplier tubes 15, one photomultiplier tube for each of the tracks within a band. The character memory 10 is rotated by means of a motor 16 to cause relative movement between the character memory 10 and the pickup means 12.

In the embodiment described herein, two of the photomultiplier tubes 15 are used to sense the timing tracks contained on the character memory 10 and generate electrical pulses which are thereafter used to provide the timing or clock signals for the remainder of the character generating apparatus, as will be described in detail hereinafter. The remainder of the photomultiplier tubes sense the digital information contained in corresponding tracks on the character memory 10, and the electrical signals produced thereby are used to control the position of a beam of energy, such as the electron beam in a cathode-ray tube, to form a character by moving the beam to a plurality of predetermined locations within a character field. Appropriate switching circuitry is provided to select the photomultiplier output to direct this character generating function in response to external commands.

The electrical output of each photomultiplier tube 15 is applied to a character generator circuit 20, the function of which is to sense the digital information contained within a selected one of the character tracks and convert that information into

control signals, hereinafter described as character generating signals, which are then applied to the vertical and horizontal deflection amplifier circuits 21 and 22 for the cathode-ray tube 25. The character generator circuit 20 also controls the energization of the cathode-ray tube beam generating means and energizes the beam only in those areas which form a part of the character to be displayed.

A control record, such as a magnetic tape 27, passes through a tape reader 28 where it is read and the electrical output fed into a buffer 30. Of course, other types of control means, such as the output of a computer or paper tape, may be used in supplying the control signals to the buffer 30. The control record 27 contains information relating to, but not limited to, character selection, intercharacter and interword spaces, and leading instructions when the system is used as a phototypesetter.

The buffer 30 accepts information from the control record at its optimum read out rate, and then transfers that information to the decoder circuit 31 at a rate which can be accepted by the phototypesetting system. Different control functions will take differing amounts of time, and even the generation of certain characters will take longer than the generation of other characters. The output of the decoder 31 is applied to the control circuit 35 which in turn supplies the character positioning signal to the horizontal and vertical circuits 21 and 22 for positioning the electron beam of the cathode-ray tube, and thus the entire character, prior to the generation of each character. Selection among the characters within a band on the character memory 10 is determined by another output from the decoder 31 to the character selection circuit 36.

In the preferred embodiment of this invention, the cathode-ray tube displaying the characters uses electromagnetic deflection means, and both the character positioning and character generating signals are applied to modify the current through the same deflection means. It has been found that this arrangement is to be preferred, especially when characters of typesetting quality are to be generated. Thus, amplifier circuit 21 supplies the current through an electromagnetic coil 37 controlling the vertical location of the beam, and in like manner, the horizontal amplifier circuit 22 controls the current through the electromagnetic coil 38 controlling the horizontal location of the beam. Both the vertical and horizontal amplifier are responsive to voltages supplied by the control circuit 35 and the character generator circuit 20. Thus, the character positioning signals position the beam to locate the character horizontally and vertically on the face of the cathode-ray tube while the character generating signals actually develop the character on the face of the cathode-ray tube. When used in a phototypesetting operation, the image of the characters so formed are recorded by photographic materials such as film or paper.

In a typesetting system the characters developed on the face of the cathode-ray tube 25 in FIG. 1 will have different widths. The letter *a*, for example, may be assigned a width value of Wa , while the letter *i* has a width value of Wi and the letter *m* has a width value of Wm . Each of these width values will depend upon the type and style of the font being generated, but normally characters such as those illustrated in FIG. 1 will be positioned automatically after the preceding character has been generated by relocating the cathode-ray tube beam, the distance which it moves being determined by the width of the previously formed character. With the type of character generator described herein, each of the characters stored on the character memory 10 has a width code associated therewith, and this width code is multiplied by the horizontal point size of the character to be generated, as determined by a signal from the control record 27. This multiplication occurs in the control circuit 35, and the horizontal character positioning signal is modified to reposition the cathode-ray tube beam after the character generation has been completed.

Referring now to FIG. 2, the character memory 10 includes a pair of clock tracks 40 and 41, a several character tracks 42. In FIG. 3, the portion of the character memory 10 includ-

ing the two clock tracks and a single character track is shown in detail. The information representing a character is recorded in serial form, although it could be recorded in parallel form in several, usually adjacent, character tracks with a corresponding decrease in the length of the track required to store the character information, but with an increase in the number of readout devices required to convert the recorded digital information into electrical signals.

The digital information for generating a single character may be repeated several times within a single discrete character track 42 in order to provide for more rapid access to the character data. As shown in FIG. 2, the character track 42 contains four repetitions of the same information, indicated at A, B, C and D. To increase the accessibility of the character information even further, each of the repetitions is divided into a plurality of sections, indicated by the numerals I, II and III. While only three sections are shown within reach of the repetitions, it is to be understood that the character information may be divided into any number of sections, the number of sections depending upon the amount of character information required to generate the character and the amount of other information which is associated with the character information in each section.

Certain disjointed characters, such as the letter *i* shown on the face of the cathode-ray tube in FIG. 1, are formed from more than one section since the cathode-ray tube beam does not move through a location which does not form a part of the character itself. Thus, moving from the main body portion of the letter *i*, for example, to the dot above the letter would require that the letter be divided into at least two sections, one for the main body portion and another for the dot above the letter.

The digital information for each of the sections within a single repetition of the character contains certain functionally similar data, such data including, for example, a unique code indicating the "start of section," a group of codes labeled "control data" which function in part to identify the starting coordinates of that section with respect to the remainder of the character and to identify the size of the character recorded, another group of codes labeled "character generating data" representing the instructions for directing the beam to form that section of the character, and an "end of section" code. It is understood that the "start of section" and "end of section" codes could be eliminated provided appropriate circuitry were included to sense the occurrence of the beginning of the control data associated with each of the sections. It has been found, however, that more reliable operation of the character generator is possible if a relatively small amount of space is used to provide unique codes indicating the start and the end of each section.

In the preferred embodiment of this invention the "control data" contains the following codes: a parity code which is used by the control circuit to sense whether the entire group of control data is properly and accurately recorded prior to permitting generation of the character; a normalized width code indicating the width of the character which has been recorded in the character generating portion of the character track; a code which functions to indicate the point size of the recorded character and also to control the duration the cathode-ray tube beam is allowed to remain energized at each spot location to permit characters of different sizes to be generated from a single character generating memory without significant variations in the recorded density of the character generated; horizontal and vertical starting coordinates which identify the position of that section of the character with respect to the remainder of the character; and a code indicating the number of sections required to generate a complete character. While this control data is shown recorded in the same track as the character generating data, all or some of this data may be recorded in a separate track or tracks which could be common to more than one character track.

While the character memory means in the preferred embodiment of this invention is an optically encoded disc capa-

ble of rotating at high speeds, it is understood that other types of character memories may be used to provide the digital information required for forming characters of typesetting quality, such character memories including but not limited to core memory devices, diode matrix devices, and magnetic drums or discs.

FIG. 4 is a diagram showing the locations which the cathode-ray tube beam will move in response to instructions from the character memory. A total of seven instructions are included in the preferred embodiment of the invention to move the beam from its present location, shown at 45 in the center of the diagram, to one of the locations immediately adjacent its present location. While there exists a total of eight locations adjacent the center location, only seven are used in the preferred embodiment. The instruction for moving the beam to one of these immediately adjacent locations is given by a three-bit or octal code stored in one of the character tracks 42 on the character memory 10, identified in FIGS. 2 and 3 as the character generating data. In the embodiment described herein, these instructions are stored in the character track in serial form although, as mentioned previously, these instructions could also be given in parallel form.

The instruction for moving the beam to the location to the immediate right of the previous location is given by the instruction "0," represented by the octal code 000. Similarly, the instruction for moving the beam to the upper right is given by the instruction "1" represented by the octal code 001. The only instruction which is not used for directing the beam to an immediately adjacent location is the instruction "7," represented by the octal code 111, which code is used as part of the start of a section or the end of a section codes. It is apparent that by careful arrangement of the instructions, it would not be necessary to have the beam move to one or more of the locations immediately adjacent its present location, or in this example, to the lower left.

FIG. 5 shows the letter *a* formed from such a series of instructions. Of course, the actual character formed on the face of the cathode-ray tube consists of a plurality of spots, of predetermined size, and not the numerals as shown in FIG. 5, although these numerals are shown to assist in understanding the instructions which are given by the character memory to the character generated circuits in forming the character.

These character forming instructions are found in serial form in the character track 42 of the character memory 10. The character shown in FIG. 5 has been divided into three sections, corresponding to the three sections into which the character track has been divided, as shown in FIG. 2. Each of the sections has a starting coordinate, that is, a location within the character field where the cathode-ray tube beam is first positioned before the series of instructions are given to position the beam to immediately adjacent locations to form the character. The starting coordinates for section I are identified as X_1, Y_1 , while the starting coordinates for section II are identified as X_2, Y_2 , and the starting coordinates for section III are identified as X_3, Y_3 . Referring to section II, for example, after the beam is positioned to the starting coordinates X_2, Y_2 , the following instructions are given in serial form: 2, 2, 2, 2, 4, 5, 5, 5, 5, 2 ..., and the beam is directed to a plurality of locations, each determined by continued reference only to the preceding location.

Referring now to FIG. 6, which is an enlarged view of a portion of section III, with the beam at the position identified by the reference numeral 46, the instruction "5" would position the beam at the location immediately therebelow and be energized to illuminate that portion of the cathode-ray tube face and form a single spot. Thereafter, another instruction "5" would be given to position the beam to the location immediately therebelow and is again energized for a predetermined time. Thereafter, the instruction "4" is given and the beam positioned to the location immediately to the left of its previous location. By reference to FIG. 4, which shows the direction of travel of the beam in response to the various instructions, one can trace out the generation of the entire

character as the beam is positioned one step at a time to immediately adjacent locations. Thus, the character is formed by a series of incremental horizontal and vertical movements of the cathode-ray tube beam.

It is noted that the beam is only positioned at those locations which form a part of the character to be displayed and never occupies a location which forms no part of the character. Using this method of character generation, no time is wasted in moving the beam to locations which cannot be utilized and therefore the speed of character generation may be increased. Also, only a 3-bit code is required to relocate the beam since reference is made to its previous location when generating the character.

Each of the spots forming the character are consistently spaced apart, that is, the distance in the X direction between spots remains constant throughout the generation of the character, and the distance in the Y direction also remains constant, although the X and Y distances may or may not be different. Also, each of the spots within a single character is of the same size, and the spots may either occupy an area so that one spot overlaps an adjacent spot or the spacing may be adjusted so that the area covered by one spot is entirely separate from the area covered by any other spot.

FIG. 7 is a simplified electrical block diagram showing the general arrangement of the various circuit and structural components which make up a complete phototypesetting system. The control record 27, which mentioned previously could be either a magnetic tape, a punched paper tape, or the output of a computer, is read by a reader 28 and the information contained therein converted into electrical signals which are applied into a buffer storage device 30. In the case of a magnetic tape, since a significant amount of useable space is used in providing the intra record gap, it is highly desirable to store and utilize as much information as possible during each movement of the tape. Accordingly, the buffer 30 is so designed that it can accept and store temporarily several hundred bytes from the control record and then release the stored information into the decoder 31 at a variable rate.

The control record 27, among other things, selects the point size of the characters to be displayed, the type of font to be displayed, interword spaces, the amount of leading, and other similar phototypesetting functional commands. The control record also selects the characters to be displayed in sequence, and if used in a phototypesetting system, the control record supplies the proper interword space to create justified lines of type.

The outputs of the decoder are therefore applied to the character generator 20 to select one of the plurality of character memories 10 to be read, to select one of the bands on the selected character memory, and to select a single one of the tracks within the selected band to provide the instructions which control the minor deflection signals to the cathode-ray tube and thus the character generated.

The decoder 31 also supplies signals to the control circuit 35. These control signals include interword spaces for storage in the space memory circuits 50, which in the preferred embodiment contains three registers. The control signals may also include a code indicating the point size of the character to be displayed, which data is stored in the character size circuit 52, and leading information for storage in the leading control circuit 53. The decoder may also supply a signal to the vertical rule generator 54.

When the control record 27 indicates that a particular character is to be displayed, the control data associated with the character generating data indicating the normalized point size of the character will be applied along line 55 to the character size circuit 52, and that information, along with the point size of the character applied to the character size circuit 52 along line 56 from the decoder 31, will cause the character size circuit 52 to produce an output to modify the status of the horizontal scale register 57 and the vertical scale register 58. The status of the horizontal and vertical scale registers ultimately determines the size of the character displayed on the

face of the cathode-ray tube 25. The character size circuit also supplies a signal which is applied to the horizontal accumulator 60, and when the character generation has been completed, the horizontal accumulator will alter the horizontal character positioning voltage to reposition the beam permitting the generation of a subsequent character without further space commands from the control record 27. In other words, the output of the character size circuit 52 will result in the proper intercharacter spacing being supplied automatically.

The horizontal position of the characters on the face of the cathode-ray tube beam is controlled by the magnitude of the character positioning voltage, which voltage is supplied by three components in the preferred embodiment of the typesetting system described herein, including the major horizontal linear digital to analogue converter or D/A 61, the major horizontal nonlinear D/A 62 and the interpolation D/A 63. The output voltage from each of these components is determined by the status of the horizontal accumulator 60.

It is well understood by those skilled in the art that the deflection currents necessary to move the beam in equal increments across the cathode-ray tube are not necessarily equal themselves, the amount of variation depending on the quality and type of the tube used. This is due to the varying length of the beam as it moves horizontally across the tube face, and to the change in angle at which the beam strikes the tube face. Thus, it is necessary to supply a nonlinear deflection current to the deflection coils surrounding the tube if equal increments of spacing are to be created on the face of the tube. It is also recognized by those skilled in the art that a different focusing voltage is necessary for proper focusing of the electron beam, depending upon the horizontal position of the beam with respect to the tube face.

The major horizontal linear D/A 61 responds to those registers in the horizontal accumulator representing the most significant digits stored therein, and supplies more than 90 percent of the signal to the horizontal deflection amplifier circuit 22 which controls the current through the horizontal deflection coil on the cathode-ray tube 25. While not shown in detail, the major horizontal linear D/A consists of a plurality of current summing resistors which may be connected into the input circuit of an operational amplifier in accordance with the status of the horizontal accumulator. The circuit is so designed that it is capable of supplying a majority, between 90 and 100 percent, of the horizontal voltage to the deflection amplifier necessary to deflect the cathode-ray tube beam.

The major deflection nonlinear D/A 62 comprises a plurality of circuits which are selected by the status of the horizontal accumulator 60. In the preferred embodiment of this invention, 48 separate circuits are provided, each supplying a different signal for its corresponding portion of the cathode-ray tube. Thus, the tube face is divided into 48 equal increments, with each of the nonlinear D/A circuits supplying the necessary voltage for its corresponding increment. By adding a small amount of voltage to that produced by the major horizontal linear D/A 61, the selected one of the major horizontal nonlinear D/A circuits will correct for the nonlinearities in the cathode-ray tube and associated components.

The major horizontal nonlinear D/A 62 also supplies voltages for controlling the focus of the cathode-ray tube beam in accordance with the horizontal position of the beam. Furthermore, these circuits supply reference voltages used by the character generating circuits and insure that the characters are properly proportioned and have the correct size, independent of their horizontal position on the cathode-ray tube face.

The interpolation D/A 63 modifies one of the outputs of the major horizontal nonlinear D/A 62 and adds that output to the outputs of both the major deflection linear D/A 61 and the nonlinear D/A 62. The interpolation D/A output is controlled by the status of the least significant digits stored in the horizontal accumulator 60. While the horizontal nonlinear D/A 62 divides the face of the cathode-ray tube into 48 equal segments, the interpolation D/A 63 further divides each out-

put of the nonlinear D/A into 255 segments. Accordingly, for a 10-inch cathode-ray tube, having an 8½-inch writing surface, the beam may be positioned horizontally within 0.000692 inch by the combined outputs of the major horizontal linear D/A 61, the nonlinear D/A 62, and the interpolation D/A 63.

One of the outputs of the major horizontal nonlinear D/A 62 is a horizontal reference voltage which is supplied to the interpolation D/A 63, as previously mentioned, and also to the horizontal scale D/A 65. This reference voltage is modified in the horizontal scale D/A 65 by the horizontal scale register 57, and the modified voltage is applied as a reference voltage to the character generating horizontal D/A 66. As will be explained in reference to the description of the character generator circuit, the character generating horizontal D/A supplies the voltages to the horizontal deflection amplifier 62 for the purpose of generating the selected character.

A vertical reference voltage from the major horizontal nonlinear D/A 62 is supplied to the vertical scale D/A 67, the leading D/A 68, and the vertical rule D/A 69. The vertical scale D/A 67 functions similar to the horizontal scale D/A 65 in that it modified this vertical reference voltage in accordance with the status of the vertical scale register 58, and this modified voltage is supplied to the character generating vertical D/A 70. The character generating vertical D/A is the minor vertical position controlling means and modified the vertical reference voltage under direction of the character generator 20 to position the beam of the cathode-ray tube during character generation.

The vertical position of the film with respect to the cathode-ray tube face is controlled by the leading control circuit 53. This control circuit has two outputs, a first output on line 71 to the leading motor 72 which physically moves the film 73 vertically with respect to the face of the cathode-ray tube 25. A lens system 74 focuses the images formed on the cathode-ray tube face onto the emulsion of the film 73. The leading motor 72 is a stepping motor, in the preferred embodiment of the invention, which moves through a plurality of incremental steps in response to the status of the memory registers contained within the leading control circuit 53. The second output of the leading control circuit is connected to the leading D/A for the purpose of positioning the characters vertically thus allowing interpolation between the steps of the stepping motor and the simultaneous leading of the film and the generation of characters.

A means, not shown, permits the leading operation to proceed at the same time the characters are being formed on the cathode-ray tube face. This is accomplished by modifying the vertical deflection voltage through the leading D/A in response to the vertical position of the film as it is moving vertically. A feedback transducer responsive to the actual position of the film is used to supply the necessary control signals to the leading D/A 68 to maintain the proper relationship between the characters and the photographic material recording those characters.

An oblique D/A 76 permits italic like characters to be formed by modifying the horizontal deflection current in synchronism with changes in the vertical position of the beam.

The beam control circuit 77 energizes the beam for a predetermined period of time at each location of the beam during character generation under the control of the character generator 20. The time interval is selected by a signal on line 78 from the character size circuit 52.

Reference is now made to the electrical block diagram in FIG. 8 showing the character generator used in the preferred form of this invention. The output of one of the photomultiplier tubes sensing the digital character information contained on one band of the character memory 10 is selected by the character section circuit 36, shown at the upper left, and that output is applied to the input shift register 81. A clock system 82 senses the clock tracks recorded on the character memory and functions to control the sequence of operation of the character generator. Several outputs are available from the

clock system for applying control signals at the proper time to cause reliable operation of the character generator. A more complete diagram of the clock system may be found in FIGS. 11A and 11B.

Once character selection has been made, the data is shifted through the input shift register until a "start of section" code is detected. At the same time, an inhibit is placed on the remainder of the system which will remain until character generation is completed. In this embodiment of the invention, the "start of section" code is represented by the digital code 1110, and is shown at the extreme left in track 42 in FIG. 3.

Nineteen bytes of information, each byte consisting of three bits, are used for the storage of the control data, as shown in FIG. 3, although interspersed at predetermined locations within each byte are fill bits which serve no other purpose than to prevent the occurrence of false start of section and end of section codes. While these fill bits are used in the control data, they are not in fact part of the character generating data. The control data which is associated with each of the character generating tracks 42 contains a single bit parity code, a 9-bit normalized width code, a 5-bit code representing the Proportional REciprocals Disc Point Size, or "PREDIPS" code, an 8-bit code representing the X starting coordinate for that section, an 8-bit code representing the Y starting coordinate for that section, and a 6-bit code indicating the number of sections required to form the character. Thus, the control data consists of 37 bits which are distributed among the 19 bytes of information assigned to represent the control data.

When the first "start of section" code is sensed the start of section detector 83, all of the registers in the character generating circuit are reset and the control data which follows is entered into appropriate registers under the direction of the register entry counter 84. The register entry counter directs that the first bit be applied through the gates to the parity error detector 85 and recorded therein. The next nine bits are routed by means of the gate 86 to the normalized width register 87. This data represents the horizontal width of the character recorded in this track of the character memory, and when multiplied by the actual point size of the character as determined by the control record, will alter the status of the horizontal accumulator 60 and assist in repositioning the cathode-ray tube beam after the entire character has been formed.

The next five bits of data are routed by means of gate 86 into the "PREDIPS" register as where this information will be used to control the size of the character generated and the duration the beam generating the character remains on in each location.

The register entry counter 84 thereafter directs the gate 86 to route the next eight bits of control data information into a first reversible counter means or the X location up-down counter 90, and the following eight bits of control data information into a second reversible counter means or the Y location up-down counter 91. The status of the X and Y location up-down counters controls the output of the horizontal character generating deflection D/A 66 and the vertical character generating deflection D/A 70, respectively, and thus the location of the cathode-ray tube beam with respect to the starting position of the beam as determined by the status of the horizontal accumulator 60. The location information stored in the X location up-down counter and the Y location up-down counter will normally be different for each of the sections which make up a complete character.

The last six bits of data making up the control data is directed by the register entry counter into the section counter 92. This data indicates the number of sections required to form a complete character, and when that number of sections has been generated, an end of character signal is generated which permits the decoder circuit to resume operation.

After all of the control data, which consists of a predetermined number of bytes, has been stored in the appropriate registers, the remainder of the digital information, which comprises the character information, is decoded by the step

direction decoder 95 and gated into the X and Y location up-down counters to modify the status of these counters by as much as one incremental unit at a time, either positive or negative. The following table describes the output from the step direction decoder in response to the digital character information:

	Octal code in input shift register	Instructions to X up-down location counter	Instructions to Y up-down location counter
Instructions:			
0.....	000	Increase.....	No change.
1.....	001	.....do.....	Increase.
2.....	010	No change.....	Do.
3.....	011	Decrease.....	Do.
4.....	100	.....do.....	No change.
5.....	101	No change.....	Decrease.
6.....	110	Increase.....	Do.
7.....	111	.....	Reserved

Therefore, when the instruction "3" is given, for example, a decrement of one unit will result in the X location up-down counter and an increment of one unit will result in the Y location up-down counter, thus moving the beam upwardly and to the left to a location immediately adjacent its previous location, as shown in FIG. 5. The input shift register therefore receives these octal codes containing the instruction in a serial form, and these instructions are read into and decoded by the step direction decoder 95 in synchronism with the signals from the clock tracks on the character memory.

Although the character generating data contains no fill bits, an end of section code (1111) is not detected even though this combination of codes may be present in the character generating data, as would be the case when an instruction 3 (110) is followed by an instruction 6 (110), since this data is not interrogated for an end of section code until a predetermined clock pulse has been received. The instruction 7 (111) may, however, be incorrectly read as either a start or end of section code, and for this reason, this instruction code is not used during the generation of characters.

By moving the beam only one unit at a time, either as an increment or a decrement in the X and Y directions, a complete character may be traced on the cathode-ray tube. In the preferred embodiment, the cathode-ray tube beam is energized in response to the clock system only after the beam has been positioned, and the circuit components have had time to settle. Using this technique of character generation permits characters of typesetting quality to be formed.

After a portion of the character has been created, an end of section code, represented by the digital code 1111, is detected by the end of section detector 97 and the character generation ceases momentarily. The end of section detector 97 applies a pulse to the section counter 92 to reduce its value by one unit, indicating that one section has been completely generated. The system therefore recognizes that a specified number of sections remain to be generated and therefore character generation will continue until all the section making up that character have been generated.

As shown in FIG. 2, an "end of section code" is followed by a "start of section" code for the next section of the character. This is detected by the start of section detector 83, and the sequence of events described above is repeated except that the section counter is not reset so that it may retain the number of sections remaining which are required to form a complete character.

To insure that the control data is properly recorded, the parity error code supplied as part of the control data is used in checking to determine if all the control data has been properly recorded in the registers. The parity error detector 85 is a flip-flop which counts the number of "1" which are applied to the several data control registers. As is common practice in the data processing field, a parity check is made by counting all of the "1" present in an instruction, and supplying a parity code, if necessary, to make the total of the "1" an off value.

If a parity error occurs, the control data is assumed to be incorrectly recorded, and none of the character instructions which follow in that section will be decoded and utilized. If a parity error occurs during the first section to be processed, that is if no previous sections had been displayed on the cathode-ray tube for that character, the section counter and parity error circuits will be reset and an attempt to begin character generation will start on the next start of section code.

On the other hand, if at least one section of the character has already been generated, and a parity error occurs in a subsequent section, it is necessary to cause all subsequent sections to be skipped until a corresponding section, perhaps in a different repetition of that character, is present. For this purpose, a skip counter 99 is utilized to allow the character memory to move through a distance sufficient to permit the corresponding section to be presented. The skip counter 99 therefore assists in the identification of corresponding sections in different repetitions of the character data.

Since the control data consists of a predetermined number of digital bytes, the register entry counter 84 forms a means for counting these bytes and directing the control data to the appropriate storage registers, and after the control data is recorded, to gate the character information appearing on the input lines to the character sensing means or step direction decoder 95 and thus to the X and Y location up-down counters. Those skilled in the art will recognize that other methods of presenting the control data may be used without departing from the scope of this invention.

Referring now to the detailed logic diagrams shown in FIGS. 9 through 12, the symbols used are conventional and may be found in American Standard Graphic Symbols for Logic Diagrams published by American Institute of Electrical Engineers, 1962. FIGS. 9A through 9D show that portion of the character generator 20 which includes the register entry counter 84, the distribution gates 86, the section counter 92 and the skip counter 99.

FIGS. 10A through 10D are detailed logic diagrams including the input shift register 82, the start of section detector 83, the end of section detector 97, the step direction decoder 95, and the parity error detector 85.

FIGS. 11A and 11B are detailed logic diagrams of the clock circuit used to control the character generator.

FIGS. 12A and 12B are detailed logic diagrams showing the normalized width register 87, the PREDIPS register 88, the X location up-down counter 90 and the Y location up-down counter 91.

The interconnection among these drawings is designated as follows. Any wire carrying a signal originating on the circuit of FIG. 9 is identified by a numeral with the letter A prefix; any wire carrying the signal originating in the circuits of FIG. 10 will be identified by a numeral with the prefix B; and all lines carrying signals which originate from the clock of FIG. 11 are identified by the numeral with the prefix C.

Thus, referring to FIG. 9A as an example, the line B1 at the upper left originates from the circuit shown in FIG. 10, and would therefore be connected to the line of the same designation on FIG. 10D, found approximately at midsheet. The line identified as C4 in FIG. 9A carries the signal originating from the clock shown in FIG. 11B, approximately midway at the left edge of the sheet. The line identified as A6, however, carries the signal originating in the circuit shown in FIG. 9 and that signal is directed to FIG. 10C, the third line from the top at the upper left.

The following is a more complete description of the operation of the character generating circuits. With reference to FIGS. 11A and 11B, which together show the logic diagram for the clock circuit, the signal from the clock track 40 on the character disc, identified as ΦA , and the signal from the clock track 41, identified as ΦB , are combined in the clock circuit 82 to produce three timing signals identified as $\Phi 1$, $\Phi 2$ and $\Phi 3$ which are each 500 nanoseconds in duration. Each of the timing signals $\Phi 1$, $\Phi 2$ and $\Phi 3$ occurs at equally spaced-apart

times, and these signals are applied to pulse shaping circuits PS1, PS2 and PS3, respectively, which produce corresponding pulses each having a duration of 80 nanoseconds, with the leading edge of each being in phase with the leading edge of the Φ_1 , Φ_2 and Φ_3 signals. The outputs from these pulse shaping circuits are applied to delay line 100.

Delay line 100 has an input identified as ONS, meaning 0 nanosecond delay. This ONS input is also available as an output from the clock circuit and is identified as Φ_{40} . The delay line 100 has outputs at 100 nanoseconds, 200 nanoseconds and 300 nanoseconds after the application of any input signal, and these outputs are identified as Φ_{41} , Φ_{42} , and Φ_{43} , respectively. The Φ_{41} signal, for example, occurs 100 nanoseconds after the leading edge of each of the Φ_1 , Φ_2 and Φ_3 signals.

Within the clock system, each of the Φ_1 , Φ_2 , and Φ_3 timing signals are combined with the outputs from delay line 100, namely Φ_{40} , Φ_{41} , Φ_{42} , and Φ_{43} . These combined outputs are identified at the right in FIG. 11B and are used to control the sequence of operation of the character generator circuit 20. The output signal $\Phi_1 \cdot \Phi_{43}$ on line C56, for example, represents a signal which occurs during the Φ_1 timing signal but which is delayed by 300 nanoseconds. Similarly, $\Phi_2 \cdot \Phi_{41}$ on line C87 is a signal which occurs during the Φ_2 timing signal and which is delayed by 100 nanoseconds.

The following table will illustrate the sequence of operation in the generation of characters:

Clock signal	Description of operation
Φ_{41} (C55)	Input data from the character memory 10 is applied into the input shift register 81 (Fig. 10A) and is shifted to the left by each Φ_{41} signal appearing on line C55. In this table, the entry of a bit of data from the character memory into the shift register 81 is indicated by *.
$\Phi_1 \cdot \Phi_{43}$ (C56)	When the start of section code (1110) is detected by the start of section detector 83, the LOAD FF (flip-flop), Fig. 10B, is set. This causes the following operation to occur.
$\Phi_{41}, \Phi_2 \cdot \Phi_{41}$ (C87)	*. An output will appear on line B1 for each Φ_{41} clock pulse which causes the register entry counter 84 (Fig. 9A) to increment one step. In this case, the register entry counter is set to step 1.

ENTRY OF CONTROL DATA INTO NORMALIZED WIDTH REGISTER	
Φ_{41}	*
$\Phi_3 \cdot \Phi_{43}$ (C4)	Data from the character memory temporarily stored in the input shift register 81 is transferred to NW8 (normalized width register 87, stage 8), (Fig. 12B). The data stored in FFO (the first stage of the input shift register 81, Fig. 10A), is transferred via line B11 to gates 86 (Figs. 9A and 9B). In this step, the register entry counter 84 directs the data stored in FFO via line A24 to NW8.
Φ_{41}	*
$\Phi_{41}, \Phi_2 \cdot \Phi_{41}$	*. Increment the register entry counter 84 to step 2.
Φ_{41}	*
$\Phi_3 \cdot \Phi_{43}$	Transfer data from FF1 and FF0 in the shift register 81 to NW7 and NW6 via lines A30 and A31, respectively.
Φ_{41}	*
$\Phi_{41}, \Phi_2 \cdot \Phi_{41}$	*. Increment the register entry counter 84 to step 3.
Φ_{41}	*
$\Phi_3 \cdot \Phi_{43}$	Transfer data from FF1 and FF0 in the shift register 81 to NW5 and NW4 via lines A34 and A35, respectively.
Φ_{41}	*
$\Phi_{41}, \Phi_2 \cdot \Phi_{41}$	*. Increment the register entry counter 84 to step 4.
Φ_{41}	*
$\Phi_3 \cdot \Phi_{43}$	Transfer data from FF1 and FF0 in the shift register 81 to NW3 and NW2 via lines A38 and A39, respectively.
Φ_{41}	*
$\Phi_{41}, \Phi_2 \cdot \Phi_{41}$	*. Increment the register entry counter 84 to step 5.
Φ_{41}	*
$\Phi_3 \cdot \Phi_{43}$	Transfer data from FF1 and FF0 in the shift register 81 to NW1 and NW0 via lines A42 and A43, respectively.

ENTRY OF CONTROL DATA INTO PREDIPS REGISTER	
Φ_{41}	*
$\Phi_{41}, \Phi_2 \cdot \Phi_{41}$	*. Increment the register entry counter 84 to step 6.
Φ_{41}	*
$\Phi_3 \cdot \Phi_{43}$	Transfer data from FF1 and FF0 in the shift register 81 to PREDIPS register 88 (Fig. 12A), stages P4 and P3 via lines A46 and A47, respectively.
Φ_{41}	*
$\Phi_{41}, \Phi_2 \cdot \Phi_{41}$	*. Increment the register entry counter 84 to step 7.
Φ_{41}	*
$\Phi_3 \cdot \Phi_{43}$	Transfer data from FF1 and FF0 in the shift register 81 to P2 and P1 via lines A50 and A51, respectively.

Clock signal	Description of operation
Φ_{41}	*
$\Phi_{41}, \Phi_2 \cdot \Phi_{41}$	*. Increment to the register entry counter 84 to step 8.
Φ_{41}	*
$\Phi_3 \cdot \Phi_{43}$	Transfer data from FF1 in the shift register 81 to P0 via A25.
ENTRY OF CONTROL DATA INTO X-LOCATION UP-DOWN COUNTER	
Φ_{41}	*
$\Phi_{41}, \Phi_2 \cdot \Phi_{41}$	*. Increment the register entry counter 84 to step 9.
Φ_{41}	*
$\Phi_3 \cdot \Phi_{43}$	Transfer data from FF1 and FF0 in the shift register 81 to X-location up-down counter 90, (Fig. 12B), stage H7 and H6 via lines A28 and A29, respectively.
Φ_{41}	*
$\Phi_{41}, \Phi_2 \cdot \Phi_{41}$	*. Increment the register entry counter 84 to step 10
Φ_{41}	*
$\Phi_3 \cdot \Phi_{43}$	Transfer data from FF1 and FF0 in the shift register 81 to H5 and H4 via lines A32 and A33, respectively.
Φ_{41}	*
$\Phi_{41}, \Phi_2 \cdot \Phi_{41}$	*. Increment the register entry counter 84 to step 11.
Φ_{41}	*
$\Phi_3 \cdot \Phi_{43}$	Transfer data from FF1 and FF0 and shift register 81 to H3 and H2 via lines A36 and A37, respectively.
Φ_{41}	*
$\Phi_{41}, \Phi_2 \cdot \Phi_{41}$	*. Increment the register entry counter 84 to step 12.
Φ_{41}	*
$\Phi_3 \cdot \Phi_{43}$	Transfer data from FF1 and FF0 in the shift register 81 to H1 and H0 via lines A40 and A41, respectively.
ENTRY OF CONTROL DATA INTO Y-LOCATION UP-DOWN COUNTER	
Φ_{41}	*
$\Phi_{41}, \Phi_2 \cdot \Phi_{41}$	*. Increment the register entry counter 84 to step 13.
Φ_{41}	*
$\Phi_3 \cdot \Phi_{43}$	Transfer data from FF1 and FF0 in the shift register 81 to the Y-location up-down counter 91 (Fig. 12A), stages V7 and V6 via lines A44 and A45, respectively.
Φ_{41}	*
$\Phi_{41}, \Phi_2 \cdot \Phi_{41}$	*. Increment the register entry counter 84 to step 14.
Φ_{41}	*
$\Phi_3 \cdot \Phi_{43}$	Transfer data from FF1 and FF0 in the shift register 81 to V5 and V4 via lines A48 and A49, respectively.
Φ_{41}	*
$\Phi_{41}, \Phi_2 \cdot \Phi_{41}$	*. Increment the register entry counter 84 to step 15.
Φ_{41}	*
$\Phi_3 \cdot \Phi_{43}$	Transfer data from FF1 and FF0 in the shift register 81 to V3 and V2 via lines A52 and A53, respectively.
Φ_{41}	*
$\Phi_{41}, \Phi_2 \cdot \Phi_{41}$	*. Increment the register entry counter 84 to step 16.
Φ_{41}	*
$\Phi_3 \cdot \Phi_{43}$	Transfer data from FF1 and FF0 in the shift register 81 to V1 and V0 via lines A26 and A37, respectively.
ENTRY OF CONTROL DATA INTO SECTION COUNTER AND SKIP COUNTER	
Φ_{41}	*
$\Phi_{41}, \Phi_2 \cdot \Phi_{41}$	*. Increment the register entry counter 84 to step 17.
Φ_{41}	*
$\Phi_3 \cdot \Phi_{43}$	Transfer data from FF1 and FF0 in the shift register 81 to section counter 92 (Fig. 9D), stages S5 and S4. (If this is the first section, then the data is also transferred to the skip counter 99 (Fig. 9C), stages SK5 and SK4.)
Φ_{41}	*
$\Phi_{41}, \Phi_2 \cdot \Phi_{41}$	*. Increment the register entry counter 84 to step 18.
Φ_{41}	*
$\Phi_3 \cdot \Phi_{41}$	Transfer data from FF1 and FF0 in the shift register 81 to section counter 92, stages S3 and S2, and skip counter 99, stages SK3 and SK2.
Φ_{41}	*
$\Phi_{41}, \Phi_2 \cdot \Phi_{41}$	*. Increment the register entry counter 84 to step 19.
Φ_{41}	*
$\Phi_3 \cdot \Phi_{43}$	Transfer data from FF1 and FF0 in the shift register 81 to section counter, stages S1 and S0 and skip counter, stages SK1 and SK0.
$\Phi_{41} \cdot \Phi_{40}$ (C94)	Reset LOAD FF. If no parity error exists as indicated by PARITY FF, then set the STEP FF (Fig. 10D) to cause the following to occur.
CHARACTER GENERATION	
Φ_{41}	*
Φ_{41}	*
$\Phi_2 \cdot \Phi_{43}$	Send an "Expose" pulse to the cathode ray tube beam control circuit 77 (Fig. 7) via line B95 (Fig. 10D).
Φ_{41}	*
$\Phi_3 \cdot \Phi_{43}$	Decode character generating data in FF2, FF1 and FF0 in input shift register 81 by the step direction decoder 95 (Fig. 10A), and increment and/or decrement the X-location up-down counter 90 and/or the Y-location up-down counter 91 via signals on lines B66, B77, B68 and B69.
Φ_{41}	*
$\Phi_1 \cdot \Phi_{43}$	Monitor the data in the input register 81 for an end of section code (111) by the end of section detector 97 (Fig. 10A). If no end of section code is present, continue as follows.

Clock signal	Description of operation
φ41	*
φ2·φ43	Send expose pulse to beam control 77.
φ41	*
φ3·φ43	Decode character generating data in FF2, FF1 and FF0 and increment and/or decrement X- and/or Y-location up-down counters.
...	Repeat previous steps until end of section code is detected.
φ41	*
φ1·φ43	When end of section code (1111) is detected, an output from the end of section detector 97 will decrement the section counter 92 one unit, reset the register entry counter 84, and reset PARITY FF.
φ41	*
φ2·φ42	Reset STEP FF. If the number in the section counter 92 is zero, then the character generation is complete. Therefore a "character complete pulse" is sent to reset the CLOCK ENABLE FF (Fig. 10D), which applies a signal on line B89 to cause the remainder if the system to resume its operation. If the section counter 92 is not equal to zero, then the sequence of operation returns to the beginning of this table and the next section of the character is generated in the same manner as described above.

While the form of apparatus herein described constitutes a preferred embodiment of the invention, it is to be understood that the invention is not limited to this precise form of apparatus, and that changes may be made therein without departing from the scope of the invention which is defined in the appended claims.

We claim:

1. Apparatus for providing a graphical configuration by sequentially directing a radiant energy beam to preset image positions to form a desired pattern of images on a radiant energy responsive surface to define a said configuration, and comprising:

means for sequentially supplying a plurality of sets of beam direction command signals with each said set providing only the direction for the beam to proceed from one image position the next of said preset image positions along either a path parallel to one of first and second mutually perpendicular coordinate axes or askew therefrom; deflection control means for sequentially deflecting said beam in accordance with said command signals from one said image position to the next said image position so that for each directional command said beam is positioned so that adjacent image positions are spaced by predetermined increments along paths respectively parallel to said axes, and

beam control means for unblanking said beam only at each of said preset image positions.

2. Apparatus as set forth in claim 1, wherein said deflection control means includes circuit means for varying the incremental spacing between adjacent image positions along paths parallel to at least one of said axes.

3. Apparatus as set forth in claim 1, wherein said sets of beam direction command signals are coded signals, each set being representative of a specific beam direction and said deflection control means includes direction command signal decoding means for decoding each set of coded command signals and providing therefor either a first coordinate signal representative of commanded directional movement along a path parallel to said first coordinate axis or a second coordinate signal representative of commanded directional movement along a path parallel to said second coordinate axis or both said first and second coordinate signals representative of commanded directional movement along a path askew from said axes.

4. Apparatus as set forth in claim 3, wherein said first and second coordinate signals are each either positive or negative signals representative of the relative direction along said axes, and first and second reversible counter means for respectively receiving said first and second coordinate signals and providing first and second count signals respectively indicating the commanded first and second coordinate axis position of the image position corresponding to the commanded directional movement.

5. Apparatus as set forth in claim 4, wherein said first and second count signals are digital signals, first and second digital

to analog means for respectively receiving said first and second count signals and providing first and second analog deflection signals for incrementally deflecting said beam for each said set of directional command signals.

5 6. Apparatus as set forth in claim 5, including means for varying the magnitude of said first and second analog deflection signals dependent upon the location of said beam on said beam on said beam responsive surface to compensate for non-linear beam responsive characteristics so that said incremental spacing along each of said axes is maintained relatively constant as configurations are formed at different locations on said surface.

10 7. Apparatus as set forth in claim 4, wherein a said configuration is formed in sections with each section defined by a plurality of said images and wherein said sequentially supplying means provides said plurality of sets of beam direction command signals for one section at a time and provides for the commencement of each section a coded pattern of section starting signals.

15 8. Apparatus as set forth in claim 7, wherein said sequentially supplying means also provides a distinctive signal representative of the number of said sections required for each configuration, and counting means for counting the number of sections formed on said surface to insure that the correct number of sections are formed.

20 9. Apparatus as set forth in claim 1, including means for positioning said beam along one of said axes prior to providing the next configuration on said surface, accumulator means effective to control the output from said configuration position controlling means to establish the location at which the entire configuration will be formed; and

25 means to update said accumulator means after each said configuration is formed so that said positioning means repositions said beam dependent at least in part on the width width along said one axis of the last said configuration formed on said surface.

30 10. Apparatus as set forth in claim 1, wherein said surface is the display surface of a cathode-ray tube and said beam is said tube's beam and said deflection control means includes:

35 first circuit means for respectively effecting positioning of said beam to major positions along one of said coordinate axes at which desired configurations are to be formed and in accordance with beam position command signals; and

40 second circuit means for effecting additional positioning of said beam along said axis in dependence upon the selected major position of said beam to compensate for nonlinear beam response characteristics of said cathode-ray tube.

45 11. The method of forming a graphical configuration on a radiant energy beam responsive surface by directing the beam in a predetermined sequence to preset image positions, and comprising the steps of:

50 sequentially providing a plurality of coded beam direction command signals each providing only directional information for displacing said beam to proceed from one image position to the next image position along either a path parallel to one of first and second mutually perpendicular coordinate axes or askew therefrom;

55 decoding each of said command signals to obtain either a first coordinate signal representative of commanded directional movement along a path parallel to said first coordinate axis of a second coordinate signal representative of commanded directional movement along a path parallel to said second coordinate axis or both said first and second coordinate signals representative of commanded directional movement along a path askew from said axes;

60 displacing said beam for each said coded directional signal in accordance with the decoded first and/or second coordinate signals so that said beam is positioned to the next preset image position with the distances between adjacent image positions being constant along paths parallel to said respective axes; and

65 unblanking said beam only at each said image position to thereby form the desired graphical image.
